(57) **CLAIM**

The ornamental design for a battery case for a battery of a mobile communication terminal, as shown and described.

DESCRIPTION

FIG. 1 is a perspective view of a battery case for a battery of a mobile communication terminal;

FIG. 2 is a front view of the battery case for a battery of a mobile communication terminal of FIG. 1;

FIG. 3 is a rear view of the battery case for a battery of a mobile communication terminal of FIG. 1;

FIG. 4 is left-side of the battery case for a battery of a mobile communication terminal of FIG. 1;

FIG. 5 is right-side of the battery case for a battery of a mobile communication terminal of FIG. 1;

FIG. 6 is top plan view of the battery case for a battery of a mobile communication terminal of FIG. 1;

FIG. 7 is bottom plan view of the battery case for a battery of a mobile communication terminal of FIG. 1; and,

FIG. 8 is an open perspective view of the battery case for a battery of a mobile communication terminal of FIG. 1.
